Joseph D. Spiller,
By his Atty.
Henry Williams

UNITED STATES PATENT OFFICE.

JOSEPH D. SPILLER, OF MALDEN, MASSACHUSETTS.

BOOT-TREE.

SPECIFICATION forming part of Letters Patent No. 399,166, dated March 5, 1889.

Application filed January 7, 1889. Serial No. 295,676. (No model.)

To all whom it may concern:

Be it known that I, JOSEPH D. SPILLER, of Malden, in the county of Middlesex and State of Massachusetts, have invented new and useful Improvements in Boot-Trees for Rubber Boots, of which the following is a specification.

In constructing boot-trees for rubber boots according to the present method a rod extends vertically through the leg portion and screws into a nut in the foot portion. To strip the boot from the tree, this rod must be unscrewed, the leg portion of the tree pulled out, the foot portion drawn out, and the rod must be screwed into its former position. All this consumes considerable time, and the insertion of the rod into the leg portion materially weakens it.

The nature of my invention is disclosed by the accompanying drawings, in which—

Figure 1 is a longitudinal vertical section of my improved boot-tree, the leg portion being in elevation and the rubber boot shown in section in position thereupon. Figs. 2 and 3 are detailed perspectives of the joining or locking portions of the foot and leg portions, respectively, of the tree. Fig. 4 is a section of the tree taken on line *x*, Fig. 1.

Similar letters of reference indicate like parts.

A represents a rubber boot in position on the tree, of which *B* is the leg portion, and *C* the foot portion. This leg portion is made solid, no provision being made for a rod, such not being needed in my invention. The joint between the leg and foot portions is of the shape of an inverted *L*, having a vertical and horizontal portion.

D is a metallic frame or plate set vertically into the foot portion *C* next the joint, said plate being provided with two vertical arms, *D'*, and a central horizontal slot, *D''*. The plate is attached to the foot portion by a screw, *d*, or in any suitable manner, and such foot portion is recessed or cut away at *C'* at the rear of the plate for the purpose mentioned below. Furthermore, the foot portion is preferably cut away at *c c* vertically next the sides of the plate, to allow for shrinkage of the wood, and for another purpose below set forth.

E is a rod lying in a passage, *C''*, which ex-

tends from the outside of the foot *C* to the recess *C'*, said rod being provided with a head or button, *E'*, at its outer end, a stirrup, *E''*, at its inner end, and a spiral spring, *e*, between said head and stirrup. This spring holds the rod *E* normally with its head or button flush with the outside of the foot *C*; but pressure on the button forces it in so that the stirrup will lie in the slot *D''* and be substantially flush with the surface of the frame *D*.

H is a metallic plate secured to the vertical part of the joint end of the leg portion *B* by screws *h* or other suitable means. Integral with this plate is the catch *H'*, of substantially the shape shown, and having a horizontal groove, *h'*, (see Fig. 3,) adapted to fit the stirrup *E''*.

H'' H'' are ribs adapted to embrace the plate *D* and prevent horizontal sidewise movement, said ribs extending into the grooves *c c*.

To place and lock the leg and foot portions together, simply press the leg portion down into the foot portion. The catch *H'* slips down into the recess *C'* behind the plate *D*, and the stirrup *E''* catches in the groove *h'*, the slot *D''* allowing it movement. Now, when the boot-tree is in position, as in Fig 1, with a rubber boot upon it, in order to strip off the boot, the button or head *E'* is pressed by placing the thumb on the outside of the boot next the button, and, the joint being thereby unlocked, the leg *B* is readily removed from the boot, and afterward the foot *C*. As above stated, the two parts may be put together again in an instant.

In order to produce additional pressure of the locking parts against each other and to start them apart when the button is pressed, a spring, *I*, is placed in the vertical recess *I'* in the leg *B* next the joint, said spring pressing against the foot *C*. (See Fig. 1.)

Having thus fully described my invention, what I claim, and desire to secure by Letters Patent, is—

1. In a boot-tree for rubber boots, the combination of the foot *C*, recessed at *C'*, provided with the plate *D*, slotted at *D''*, the spring-rod *E*, adapted to play in the passage *C''*, and the leg *B*, provided with the plate *H* and hook *H'*, having the recess *h'*, substantially as and for the purpose set forth.

2. In a boot-tree for rubber boots, the com-

bination of the hook-plate H, secured to the leg B and provided with the ribs H'', with the plate D and foot C, the latter provided with the grooves c c next the sides of said plate, substantially as and for the purpose above set forth.

3. In a boot-tree for rubber boots, the combination of the foot portion C, provided with a locking-bolt, the leg portion B, provided

with a catch for engaging said bolt, and a spring, as I, set into said leg portion and bearing against the foot portion, substantially as and for the purpose set forth.

JOSEPH D. SPILLER.
